PILE FABRIC

Anthony M. Muldoon, Hightstown, N. J.

Application July 8, 1933, Serial No. 679,458

3 Claims. (Cl. 139—401)

This invention relates generally to improvements in tufted pile fabrics such as rugs and carpets.

One object is to provide a durable fabric that shows the same pattern on the back as on the front thereof.

Another object is to provide a fabric that is economical to manufacture on standard type looms.

10 A further object is to provide a fabric that is long wearing.

Other objects and advantages of the present invention will be obvious from the description to follow taken in connection with the accompanying drawing.

In its preferred form the invention contemplates a rug or the like woven with three shots of weft and sets of four warp threads.

The weft threads are preferably double and of 20 relatively stiff threads such as jute or the like. The warp threads are of smaller and softer material such as cotton being more flexible than the weft threads. The weft threads are laid in three planes which may be considered as the bottom 25 or lower plane, the top or upper plane and an intermediate or central plane and the pile tufts are looped around the wefts of the intermediate plane. Two of the warp threads of each set correspond with what are commonly called "chain" 30 or "binder" warps and are woven below the wefts of the bottom plane and above the wefts of the upper plane. One of these chain warps always passes beneath the central plane tuft holding wefts and the other chain warp always passes 35 above the central plane tuft holding wefts so that the tuft holding or locking wefts are held between the respective chain warps. The other warp threads correspond with what are commonly termed "divider" or "stuffer" warps which 40 extend substantially straight through the fabric—one warp lying between the central plane wefts and the bottom plane wefts and the other warp lying between the central plane wefts and the upper plane wefts.

45 Figure 1 is a diagrammatic bottom plan view of a portion of one form of my improved fabric.

Figure 2 is an enlarged sectional view, showing the elements spaced apart before they are beaten or drawn together.

50 Figure 3 is a view similar to Figure 2 but with the parts closer together.

Figure 4 is a sectional view at right angles to the view of Figure 2.

55 Figure 5 is a modified form with only three

warp threads, the bottom substantially straight warp thread of Figure 1 being omitted.

Figure 6 is another modified form similar to the form in Figure 5 but with the upper substantially straight warp thread of Figure 1 being omitted. 5

My improved fabric includes parallel rows of tufted piles 9 and is of the three-shot variety, comprising intermediate weft threads 10, upper weft threads 11 and lower weft threads 12. These are all double—preferably as shown. The piles 9 10 are made of wool yarn and the weft threads are made of jute or any other material suitable for the fabric desired. The wefts are shown as comprising two threads but it will be understood that in its broadest aspect single threads might be 15 used.

Extending lengthwise of the fabric is a warp thread 13 positioned between the upper weft threads 11 and intermediate weft threads 10; and extending in the same direction between the intermediate wefts 10 and lower wefts 12 is another warp thread 14. While these warps divide the wefts they of course stuff or add body to the fabric.

It will be understood that in practice a weight 25 is placed at each end of these warps 13 and 14 in order to keep them as straight as practicable while weaving, yet when the fabric is closely woven the tension of the weft threads bearing against the said warps 13 and 14 tends to crimp 30 the same more or less.

Interwoven around and between the wefts 10, 35 11 and 12, and the warps 13 and 14, is a pair of so-called "chain" or binder warps 15 and 16. The chain warps 15 are woven under the lower wefts 12, up and to one side of and over the intermediate wefts 10 and up and over the upper wefts 11, and then down and under the next lower wefts 12 and so on throughout the length of the fabric. The chain warps 16 are woven 40 under the lower wefts 12, up and to the other side of and under the intermediate wefts 10 and up and over the upper wefts 11 and then down and under the next lower wefts 12 and so on throughout the length of the fabric. By reason of this 45 weave, the chain warps 15 and 16 straddle the intermediate wefts 10. It will thus be noted that there are two warps 15 and 16 under the lowermost wefts 12, and the same two warps 15 and 16 are over the upper wefts 11. Also that there are 50 two warps, numbered 14 and 16, under the intermediate wefts 10 and two warps 13 and 15 over the intermediate wefts 10. There are two warps, 13 and 14, under the upper wefts 11. Over the lower wefts 12 are the two warps 13 and 14. 55

The pile tufts 9 are woven around the intermediate wefts 10 which are supported by the warp threads 14 and 16 and held down by warps 13 and 15. The chain warps 15 prevent the intermediate wefts 10 from slipping directly above the lower wefts 12, and the chain warps 16 prevent the same wefts 10 from slipping directly below the upper wefts 11. By reason of this construction the bights 17 of the tufts are positioned between the wefts 12 and 11 and are exposed at the rear of the fabric, and yet held up substantially free from contact with the floor. The pile tufts are shown held in an upright position by the associated threads.

From the foregoing it will be seen that the tufts stand straight upward, and that the bights of the tufts are exposed but removed from the lowermost plane of the fabric so that they form no part of the wearing surface of the fabric, thus increasing the life of the fabric.

The four warps 13, 14, 15 and 16 form a series of four throughout the fabric and the piles 9 are positioned between the chain warps 15 and 16 of each series. This construction forms a firm and durable fabric of attractive appearance of sufficient flexibility to permit easy handling and yet not sleazy or likely to curl up when in use.

In the form illustrated in Figure 5, the upper stuffer or dividing warps 13 above described have been omitted.

In Figure 6, the lower stuffer or dividing warps 14 have been omitted.

These modifications are cheaper, lighter and more flexible and have some of the advantages of the preferred form but they lack the body and durability of the preferred form.

Other changes and modifications in details might be resorted to without departing from the spirit of the invention.

In all forms it will be seen that the pile threads or tufts which form the design or pattern are also visible at the back.

I claim:

1. A tufted pile fabric comprising three sets of weft threads, pile tufts looped around one set of weft threads, a single series of crimped warp threads dividing one set of said wefts from the other two sets into different horizontal layers, said latter two sets of wefts being unseparated horizontally from each other by said single series of crimped warp threads, two sets of weft threads being above and one set of weft threads being below the crimped warps, one of the layers above the crimped warps comprising the wefts supporting the tufts, a second layer above the crimped warps comprising a second set of wefts and another layer below the crimped warps comprising the third set of wefts, and pairs of chain warps in series, one warp thread of each pair passing under the wefts of the third set below the crimped warps, upwardly and to one side of said tuft supporting wefts and downwardly over said other

set of wefts above the crimped warps, the other series of each of said pairs passing under said wefts of the third set below the crimped warps, upwardly and to the other side of said tuft supporting wefts and downwardly over said other set of wefts above the crimped warps, said pile tufts being held laterally between the two series of warps comprising the chain warps and below the crimped warps whereby the bights of the tufts are visible at the back of the fabric.

2. A tufted pile fabric comprising three sets of weft threads, pile tufts looped around one set of weft threads, a single series of crimped warp threads dividing one set of said weft threads from the other two sets into different horizontal layers, said latter two sets of wefts being unseparated horizontally from each other by said single series of crimped warp threads, one set of weft threads being above and the other two sets being below the crimped warps, the layer below the crimped warps comprising the weft threads supporting the tufts and a second set of weft threads and the other layer above the crimped warps comprising the third set of weft threads, and pairs of chain warps in series, one warp thread of each pair passing under the second set of weft threads below the crimped warps, upwardly and to one side of said tuft supporting wefts and upwardly and over the other set of weft threads above the crimped warps, the other series of each of said pairs passing under said second set of weft threads below the crimped warps, upwardly and to the other side of said tuft supporting weft threads and upwardly over said other set of weft threads above the crimped warps, the pile tufts being gripped laterally between adjacent chain warps and being disposed below the crimped warps whereby the bights of the tufts are visible at the rear of the fabric.

3. A tufted pile fabric comprising three sets of weft threads, each set being on a different horizontal plane, pile tufts looped around one set of weft threads, a single series of crimped dividing warp threads interwoven between the weft threads of one plane and the weft threads of the other planes, the weft threads on the other planes being unseparated horizontally by said single series of crimped warp threads, pairs of chain warps in series, one warp thread of each pair being interwoven below the weft threads in the lowermost plane, upwardly and to one side of the tuft supporting weft threads and above the weft threads in the other plane, and the other series of each of said pairs being interwoven below the weft threads in the lowermost plane, upwardly and to the other side of the tuft supporting weft threads and over the weft threads in the other plane, said pile tufts being positioned between the threads of the pair of chain warps and below the crimped warps whereby the pile tufts are held laterally by the chain warps and the bights of the tufts are visible at the back of the fabric.

ANTHONY M. MULDOON.
